UNITED STATES PATENT OFFICE.

HARRY E. WIGGS, OF MANNFORD, OKLAHOMA.

TOOL FOR HOLDING HOES WHILE SHARPENING THE SAME.

1,349,178.

Specification of Letters Patent. Patented Aug. 10, 1920.

Application filed October 7, 1919. Serial No. 329,157.

To all whom it may concern:

Be it known that I, HARRY E. WIGGS, a citizen of the United States, and a resident of Mannford, in the county of Creek and 5 State of Oklahoma, have invented certain new and useful Improvements in Tools for Holding Hoes While Sharpening the Same; and I do hereby declare the following to be 10 a full, clear, and exact description of the invention, such as will enable others skilled in the art to which it appertains to make and use the same.

My invention relates to an improvement in a portable tool for holding a hoe while 15 the latter is being sharpened and it consists in a holder adjustably secured to a support and adapted to receive and support the rear edge of a hoe blade at both sides of the handle.

20 In the accompanying drawings Figure 1 is a view in perspective of my improvement, and Fig. 2 is a side view of the same.

1 represents a plate like base rectangular in shape and provided with holes for the 25 passage of screws for securing it to a block of wood, and 2 is a post integral with or secured centrally to the upper face of said block and terminating at its upper end in a half bearing 3. The hoe blade holder 4 is 30 Y-shape, the side members of the bifurcated part being preferably curved in horse-shoe form so as to provide ample space between the side members for the hoe shank and handle. The lower end of the holder 4 terminates in a half bearing 5, which when secured to half bearing 3 on the post 2 by a screw carrying a thumb nut 6, forms a hinged joint which permits the holder to be 35 adjusted to any angle to suit the hoe being sharpened. The screw passes through the half bearings 3 and 5, with its head against the outer face of one of them and the thumb nut on the screw bears against the outer face of the other half bearing, so that when the 40 nut is turned to tighten the parts, the two flat faces of half bearings 3 and 5 are drawn into solid contact and are so held by friction. If desired these meeting faces of the bearing sections 3 and 5 may be serrated 45 or roughened so as to interlock and provide a positive lock for the joint.

The free ends of the two members 7 of the holder are slotted at the top to receive the rear edge of a hoe blade, which rests 50 solidly on the bottoms of the slots 8 and is locked therein by the set screws 9 mounted

in holder at one side of the slot and adapted to bear at their free ends against the blade.

With this construction the shank and handle of the hoe rest within the bifurcated portion of the holder with the cutting edge 60 of the blade uppermost and in a position where it can be readily sharpened by a file or other hand operated sharpening tool. With this arrangement after the blade has 65 been secured in the holder, the latter can be adjusted to permit the free end of the handle of the hoe to rest on the ground, or on a bench or other support and thus assist in supporting the holder in an upright position and permitting one to use a small and light block to which the base 1 is secured.

70 It is a difficult matter to sharpen a hoe on a grind stone as the handle makes it awkward to hold and manipulate. Again hoes 75 need to be sharpened often and it is necessary for the farmer to have a tool handy and as the grinding or sharpening tools now in use are too cumbersome to carry around, many farmers and gardeners support 80 the hoe on a stump or between their knees and sharpen it with a file. My device is portable and can be carried around the field and set on the ground at any point as the base block and handle of the hoe form 85 a solid support for the hoe while the latter is being sharpened.

Having fully described my invention what I claim as new and desire to secure by Letters-Patent, is:—

90 1. A tool for holding a hoe while being sharpened consisting of a base and an integral Y-shaped holder adjustably secured to the base, the upper free ends of the two side members of the holder being separated 95 sufficiently to receive the hoe shank between them and the two upper free ends of said side members being slotted to receive the rear edge of the hoe blade and clamping screws for locking the blade to the holder 100 and a screw bolt and nut for locking the holder in its adjusted position to the base.

105 2. A tool for holding a hoe while being sharpened consisting of a base plate, a post thereon, an integral Y-shaped holder adjustably secured to the post whereby the holder may be adjusted to permit the end of the handle of the hoe to rest on the ground or other support while the blade is being supported by the holder, the upper free ends of 110 the side members of the holder being separated as shown for the entrance of the

shank of the hoe handle between them, and the free ends of said side members being slotted to receive the rear edge of the blade and support the latter in position to be sharpened, clamping screws for locking the blade to the holder, and a screw bolt and nut for locking the holder in its adjusted position to the post.

In testimony whereof I have signed this specification in the presence of two subscribing witnesses.

HARRY E. WIGGS.
